UNITED STATES PATENT OFFICE.

BERTRAND S. SUMMERS, OF PORT HURON, MICHIGAN.

THRASHING MACHINE.

Application filed February 9, 1921. Serial No. 443,525.

To all whom it may concern:

Be it known that I, BERTRAND S. SUMMERS, a citizen of the United States, residing at Port Huron, in the county of St. 5 Clair and State of Michigan, have invented certain new and useful Improvements in Thrashing Machines, of which the following is a specification.

This invention relates to a new and improved thrashing machine, and more particularly to an improvement in that type of thrashing machines known as "strippers." In machines of this character the seed or seed pods are removed from the grain with 10 the minimum possible injury to the straw. In apparatus of this kind the thrashing action is applied only to the upper pod or grain-carrying end of the straw, and the straw itself is protected from abuse by the 15 machine. Such machines are particularly desirable for use in the thrashing of flax straw where both the straw and the seed are of value.

It is an object of the present invention to 20 provide a device adapted to fully remove seed pods and seeds from flax or similar straw, and which will accomplish this result without injury to the straw.

It is also an object to provide apparatus 25 of this character which is rapid and efficient in its operation, relatively simple in design and comparatively easy of construction and use.

Other and further objects will appear as 30 the description proceeds.

Broadly my invention comprises means 35 for carrying flax straw through the machine, the straw being protected from injury and the seed-carrying pods being uniformly presented to the action of the thrashing 40 means. I provide thrashing means consisting of juxtaposed rollers adapted to roll the seed pods therebetween, the rollers being moved in pairs relative to the path of the straw so that each individual straw is acted 45 upon a plurality of times by the rollers during its passage through the machine. The rollers move in such manner relative to the straw that a whipping action as well as a 50 rolling is given the seed ends.

I have illustrated a preferred embodiment of my invention in the accompanying drawings, in which—

Figure 1 is a plan view of the machine; 55 Figure 2 is an elevation of the machine;

Figure 3 is a view taken on line 3—3 of Figure 1;

Figure 4 is a cross section taken on line 4—4 of Figure 1;

Figure 5 is a longitudinal section taken 60 on line 5—5 of Figure 1;

Figure 6 is a longitudinal section taken 65 on line 6—6 of Figure 1;

Figure 7 is a fragmentary detail showing the means for laterally adjusting the flax- 70 carrying means;

Figure 8 is a side elevation of a modified form of the apparatus;

Figure 9 is a plan view of the apparatus 75 of Figure 4; and

Figure 10 is a fragmentary detail of the 80 thrashing roll mounting.

Referring to Figures 1 to 7, the machine is driven by means of the pulley 8 keyed to the shaft 9. This shaft is supported in the 85 frame 10 of the apparatus and carries the idler pulley 11 beside the pulley 8. This shaft 9 carries also the sprocket wheel 12 which is connected by sprocket chain 13 to sprocket wheel 14. The wheel 14 is carried 90 by shaft 15 which is supported by the frame 10 parallel to the shaft 9. The rigidly connected gear wheels 16 and 17 are slidably fitted upon the shaft 15 in such manner as to rotate therewith and these wheels are 95 adapted to be jointly moved longitudinally of the shaft by the shift lever 18, pivotally attached to the frame at 19. The gears 20 and 21 carried by the shaft 22 are adapted to selectively coact with pulleys 16 and 17 100 respectively. The shaft 22 also carries the sprocket wheels 23 and 24. Also in mesh with the gear wheel 20 is the gear wheel 25 carried by the shaft 26, this shaft being above and parallel to the shaft 22. This 105 shaft 26 also carries the sprocket wheel 27.

The broad pulley 28 is carried by the shaft 9 and is adapted to rotate freely thereon. The idler sprocket wheels 29 and 30 are carried by the shaft 31 located below 110 and to the right of the pulley 28, as shown in Figure 2. Similar pulleys 32 and 33 are carried on the shaft 34 below and to the left of the pulley 28. Other similar pulleys 35 and 36 are carried on shaft 37 at the left of the pulley 28, and pulleys 38 and 39 are carried on shaft 40 to the right of pulley 28. The gear wheels 41 and 42 are carried at the extreme left of the machine upon shaft 43, this shaft being carried by longitudinally 115

movable journals 44 and 45. The continuous sprocket chain 46 runs around sprockets 41, 35, pulley 28, sprockets 38, 24, 29, 32, and back to sprocket 41. Similarly the sprocket chain 47 runs parallel thereto about the adjacent series of sprockets.

The sprocket wheel 48 is carried by the shaft 49 upon the longitudinally movable journals 50, 51 at the upper left-hand side 10 of the machine, as seen in Figure 2. The sprocket chain 52 passes about this sprocket 48 and also about the sprocket 53 which is interposed between the pulleys 35 and 36 on the same shaft 37 therewith, thence about 15 the lower portion of the pulley 28, over an idler sprocket 54 interposed between the pulleys 38 and 39 upon the same shaft 40 therewith and about the driven sprocket 27 upon the shaft 26.

20 The fixed internal gear 55 is secured to the inside of the side of the frame adjacent the pulley 8 concentrically with the shaft 9. The spaced wheels 56 and 57 are secured fixedly to this shaft 9 adjacent the gear 55, 25 these wheels carrying a plurality of radially aligned pairs of shafts 58 and 59. The inner series of shafts 58 are each provided with gears 60 coacting with the internal gear 55. The shafts 58 also each carry 30 intermediate wheels 56 and 57, a gear 61 in mesh with a gear 62 carried by the shaft 59 by means of which the latter shafts are driven. The shafts 58 and 59 each extend 35 inwardly from the wheel 56 and are provided with coacting thrashing rollers 63 and 64.

A sub-frame comprising the longitudinal members 65 and 66 is carried upon the main frame and is laterally adjustable thereon 40 by means of the threaded shafts 67 and 68 which interfit with members 69 and 70 carried by the members 65 and 66, respectively, as best shown in Figure 7. This 45 sub-frame further comprises vertical members 71 and 72 and also horizontal members 73 and 74, as best shown in Figures 3 and 4.

50 Adjacent the lower portion of the machine and located approximately below the shaft 9 is the pair of rolls 75 and 76 which may be driven in any desired manner from the driven shaft of the machine. The sloping guide plates 77 and 78 are adapted to lead materially falling thereon from the machine to the rolls 75 and 76.

The form of the apparatus shown in Figures 8 and 9 comprises the frame 80 supporting the driven shaft 81. This shaft 60 carries the driving pulley 82 secured rigidly thereto. The shaft 81 also carries the driving sprocket 83 and the gear wheel 84, the latter being in mesh with the gear wheel 85 carried by the shaft 86. The shaft 86 65 is supported by the frame parallel to the shaft 81 and carries the spaced sprocket

wheels 87 and 88, these wheels 87 and 88 being located in planes upon opposite sides of the sprocket wheel 83. The idler sprocket wheel 89 is carried upon the short shaft 90 below and to the left of the wheel 83 and 70 in a plane therewith. The similar sprocket 91 is carried in the same plane at the left of the machine on the shaft 92 and the sprocket wheel 94 is also carried in this plane at the upper left-hand side of the 75 machine upon the shaft 95 supported in the adjustable journal mechanism 96. The continuous sprocket chain 97 runs around the sprocket wheels 83, 89, 93 and 94. The pair 80 of idler sprockets 98 and 99 is located below and to the left of the sprockets 87 and 88, respectively. A similar pair of sprockets 100 and 101 is located in the corresponding plane on the left side of the apparatus and above them is located the pair 85 of sprockets 102 and 103 carried on the shaft 105, which is supported by the longitudinally adjustable bearing assembly 105. The continuous sprocket chain 106 passes about the sprocket wheels 88, 99, 101 and 103. A similar chain 107 passes parallel thereto about the sprockets 87, 98, 100 and 102. The upper horizontal runs of the chains 106 and 107 are supported in parallel troughs 108 and 109, respectively. These 90 troughs are supported from the machine frame upon the resilient springs 110. The sprocket chain 97 has its lower horizontal run urged downwardly by the channel 111, the latter being resiliently urged away from 95 the machine frame by the springs 112.

The spider 113 is supported upon the frame in a horizontal position, being carried by the shaft 114, the latter being driven from the shaft 81 by the chain 126, the 105 counter shaft 114' and coacting bevel gears as shown in Figure 8. The circular rack 115 is rigidly secured to the frame concentric with the shaft 114. Each arm of the spider 113 rotatably carries a shaft 116, 110 the latter being provided with a gear 117 meshing with the rack 115. This shaft 116 is further provided with a gear meshing with a superposed gear 118, the latter being upon a superposed short shaft 119. The outer ends of the parallel shafts 116 and 119 each carry rollers 120, the rollers being in contact. As shown in Figure 10, these rollers, as well as the similar rollers of the other form of the device, may be yieldably 115 maintained in contact through the shorter shaft being journaled in a movable block 121 urged toward the longer shaft by a spring 122.

The chains 97, 108 and 109, together with 125 their cooperating sprocket wheels, are carried by a sub-frame 123 which is laterally adjustable upon the main frame 80 by means of screw-threaded shafts 124 and 125 in a manner similar to that already described in 130

connection with the sub-frame of the other form of the apparatus. This form of the machine is also provided with the chutes 77' and 78' and the cooperating rollers 75' and 76' similar to the corresponding rollers and planes in the first-described form of the device.

In the use of the form of my thrashing machine shown in Figures 1 to 7, power is applied to the pulley 8 upon the shaft 9 which serves to also rotate the shaft 15 by means of the sprocket chain 13 coacting with the sprocket wheels 12 and 14 on the two shafts, respectively. From this shaft 15 power is selectively supplied to shaft 22 by means of one or the other of the gears 16 and 17 and their coacting gears 20 and 21. This shaft 22 through the sprockets 23 and 24 drives the sprocket chains 46 and 47. These chains are continuous and through their contact with the pulley 28 for a portion of their travel serve to rotate that pulley, which turns freely on the shaft 9. The shaft 26 is driven from the shaft 22 by means of the intermeshing gears 20 and 27. This shaft 26 by means of the sprocket wheel 27 drives the sprocket chain 52, which latter for a portion of its run aids in rotating the pulley 28 passing intermediate and parallel to chains 46 and 47. The tension of these several sprocket chains may be adjusted by moving their left sprocket wheels inwardly or outwardly as desired.

The wheels 56 and 57 being keyed to the shaft 9 are rotated therewith. The engagement of the gears 60 with the fixed internal gear 55 serves to rotate the shafts 58 and through the engagement of the gears 61 and 62 to rotate the shafts 59. The pairs of rollers 63 and 64 are thus given a planetary motion.

It will be noted that the contacting faces of these rollers 63 and 64 are located substantially in the plane of the outer surface of the pulley 28.

The bundles of flax are placed upon the chains 46 and 47 at the left end of the machine and power is applied in a direction adapted to move these chains, as indicated by the arrow in Figure 2. The flax as it moves inwardly is clamped between the chains 46 and 47 and chain 52 and is carried by these chains against the pulley 28. The chains 46 and 47 press the flax straw against the pulley while the chain 52 is interposed between the straw and the pulley. As the flax is carried around the lower portion of the pulley 28 its heads project into the path of the planetary rollers 63 and 64. These rollers are rotating at a speed materially greater than that of the pulley 28, the pairs successively rolling the seed pods between them. The gear ratio 9 and rotary movement is such that during the passage of any individual bundle of straw it is rolled

between each pair of rollers a large number of times. As the straw is carried by the chains 46, 47 and 52 over the pulleys 38 and 39 and 54, the path of the chain 52 inclines upwardly and the clamping action upon the straw is released. It is carried to the right by the chains 46 and 47 and is discharged from those chains as they turn downwardly over the pulleys 23 and 24, and passes down the inclined table 79. The grain or seed and the seed pods which are broken from the straw by the action of the rollers 63 and 64 fall down to the lower portion of the machine and are guided by the inclined slopes 77 and 78 so that they pass between the pair of rollers 75 and 76. These rollers serve to crush any seed pods which have not been broken by the previous action. The material discharged from the rollers 75 and 76 is removed and is put through a fanning mill to separate the chaff from the grain or seed.

It will be observed that the direction of rotation of the rollers 63 and 64 is such as to be opposed to the direction of movement of the straw around the pulley and the rapidity of its rotation is adjusted in the design of the machine, so that there is no tendency for the head of the straw to be entirely drawn therefrom by the gripping action of these rollers as they momentarily grasp the seed bearing end of the straw.

As straw is cut in different lengths, provision in this form of the machine is made by means of the sub-frame 65, 66 whereby the pulley 28 and the sprocket wheel and chain assembly may be moved laterally toward the thrashing rollers from the position in which they are shown in Figure 1. The machine may thus be used with lots of straw varying in length. In order to accomplish this movement the several sprockets which are carried by the driven shafts extending the full width of the machine are sildable upon such shafts.

In the operation of the form of my apparatus shown in Figures 8 and 9, the flax to be threshed is placed upon the lower chains 108 and 109 at the left end of the apparatus. These chains move to the right and carry the flax under the chain 97, and these two opposed sets of chains being resiliently urged into the same plane, the flax is firmly held as it is passed through the machine. The flax is placed so that its seed-bearing heads come into the plane of the meeting faces of the rollers 120, and the shaft 114 being rotated simultaneously with the movement of the chains, the flax as it progresses is rapidly rolled by the series of rollers 120 carried by the spider. Early in its travel the rollers cross it diagonally in one direction; as it approaches the middle of its travel they pass across it parallel to its travel; and toward the close of its travel it is rolled upon another di-

agonal. The successive pairs of rollers also have a beating action upon the heads of the grain and prevent the heads from being matted or compacted together.

5 Obviously the ratio of movement of the flax and of the spider carrying the thrashing rollers may be made such as to give any desired number of rollings during the passage through the machine. The straw 10 after the thrashing is carried out of the machine upon the lower chains 108 and 109 and is discharged at the right end of the machine. The seeds and seed pods broken from the straw by the thrashing action 15 drop to the lower part of the machine and are carried by the planes 77' and 78' to the rollers 75' and 76', where any seed pods which have been discharged without being broken are here crushed to release the seeds. 20 Material discharged from these rollers is passed through a fanning mill to eliminate chaff, as in the other form of the apparatus.

Either form of my apparatus accomplishes in a very short travel a very thorough rolling of the seed-bearing head of the straw. Obstinate flax seed sometimes requires 20, 30 or even more rollings to properly remove the grain. If the straw 25 were passed by any mechanism through 20 or 30 pairs of rolls, a very large and cumbersome machine would be required. Further, the continued rolling without agitation between rollings causes the heads to 30 become compressed into a compact mass, which prevents rather than assists in the thorough removal of the seed. The gear ratios in the first form of my machine may be 35 so related that the thrashing roll carrying 40 wheel may make as high as one hundred or more revolutions to a single revolution of the wheel 28. Thus the flax bundle, while traversing half of the circumference of the wheel 28, may be rolled two hundred 45 times between pairs of thrashing rolls. This would take place if the ratios were one to one hundred, since there are four 50 sets of thrashing rolls upon the wheels. A similar amount of rolling may be secured 55 by properly relating the rate of movement of the chains and of rotation of the spider in the second form of the apparatus.

In addition to this rolling action, in both 55 forms of the apparatus the thrashing rolls have the effect of whipping the heads of the bundles of material as the rolls come in contact with each bundle head and any matting is obviated and the loose chaff and seed are knocked out and dropped into the 60 hopper, at the lower side of the apparatus.

While I have shown two preferred forms 65 of my apparatus, it is to be understood that they are illustrative only and that I may vary their design or construction within the scope of the appended claims. While

the flax has been referred to as fed in bundles, it obviously may be fed in a continuous layer if desired.

I claim:

1. In a machine of the class described, 70 means for passing the material to be threshed through the machine, and opposed thrashing rolls and means adapted to carry them into and out of the path of movement of the material through the machine. 75

2. In a machine of the class described, means for passing the material to be threshed through the machine, and a plurality of pairs of opposed thrashing rolls carried by means adapted to rotate them 80 and to carry them along a portion of the path of movement of the material in a position to engage the seed carrying portion of the material and to roll it between them. 85

3. In a machine of the class described, 90 means for passing the material to be threshed through the machine, and a plurality of pairs of opposed thrashing rolls mounted upon means adapted to give them a circulatory movement, a portion of the 95 path of said movement coinciding with the path of movement of the material through the machine.

4. In a machine of the class described, a plurality of continuous conveyor elements 95 adapted to carry material to be threshed through the machine, and a plurality of pairs of opposed thrashing rolls mounted upon means adapted to give them a circulatory movement, a portion of the path of 100 said movement coinciding with the path of movement of the material through the machine. 105

5. In a machine of the class described, a plurality of continuous conveyor elements 105 adapted to carry material to be threshed through the machine, and a planetary system of thrashing rolls adapted to engage the seed carrying portion of the material. 110

6. In a machine of the class described, 110 a plurality of continuous conveyor elements adapted to carry material to be threshed through the machine, and a planetary system of paired thrashing rolls adapted to engage the seed carrying portion of the material and successively roll it between the 115 paired rolls.

7. In a machine of the class described, a rotatable conveyor guide pulley, conveying 120 means adapted to carry the material to be threshed whereby a portion thereof is brought into engagement with the periphery of said pulley and to maintain it engaged therewith during a portion of the rotation thereof, the seed portion extending beyond the pulley, and means adapted to thresh the seed carrying portions of the material while the material is held against the pulley. 125

8. In a machine of the class described, a 130

rotatable conveyor guide pulley, conveying means adapted to carry the material to be threshed into engagement with the periphery of said pulley and to maintain it engaged therewith during a portion of the rotation thereof, and a plurality of pairs of opposed thrashing rolls carried by means adapted to rotate them and to carry them along a portion of the path of movement of the material in a position to engage the seed carrying portion of the material and to roll it between them.

9. In a machine of the class described, a rotatable conveyor guide pulley, conveying means adapted to carry the material to be threshed into engagement with the periphery of said pulley and to maintain it engaged therewith during a portion of the rotation thereof, and a plurality of pairs of opposed thrashing rolls mounted upon

means adapted to give them a circulatory movement, a portion of the path of said movement coinciding with that portion of the path of movement of the material while in engagement with the pulley. 25

10. In a machine of the class described, a plurality of continuous conveyor elements, a portion of the paths of the conveyors being substantially parallel and the conveyors being adapted to retain between them 30 for this portion of their travel material to be threshed with the seed carrying portion of the material extending beyond the conveyor, and a planetary system of paired thrashing rolls adapted to engage the seed 35 carrying portion of the material and successively roll it between the paired rolls.

Signed at Chicago, Illinois, this 1st day of February, 1921.

BERTRAND S. SUMMERS.
